L. H. BROWN ET AL

PAINTBRUSH PROTECTOR

Filed March 7, 1924

INVENTORS

Leonard H. Brown
Rudolph Mahagren

BY John A. Karsmith

ATTORNEY

UNITED STATES PATENT OFFICE.

LEONARD H. BROWN, OF NORTH PALO ALTO, AND RUDOLPH MALMGREN, OF MAYFIELD, CALIFORNIA.

PAINTBRUSH PROTECTOR.

Application filed March 7, 1924. Serial No. 697,624.

To all whom it may concern:

Be it known that we, LEONARD H. BROWN, a citizen of the United States, and a resident of North Palo Alto, in the county of San Mateo and State of California, and RUDOLPH MALMGREN, a citizen of the United States, and resident of Mayfield, in the county of Santa Clara and State of California, have invented certain new and useful Improvements in Paintbrush Protectors, of which the following is a specification.

After a brush has once been used in paint, especially the heavier brushes such as used in house painting, it must be thoroughly cleaned or some means provided to prevent access of air thereto, otherwise the oxidation of the exposed paint soon forms a hard coating on the body portion of the brush and particularly upon the brush proper at the base of the bristles. Furthermore, even when cleaned the used brush rapidly loses its pliancy and shape even when immersed in a protecting liquid.

It is one object of our invention to provide a device so formed and constructed as to be readily closed over the bristles and fitting snugly against the brush body whereby to effectively seal the same off from the air when not in use.

It is another object of our invention to provide a device of the character indicated that is so formed as to maintain the bristles in their proper compact normal wedge-shaped condition when not in use.

Furthermore, it is an object of our invention to provide a device of the character indicated provided with means for securing it firmly in a closed position on a brush.

Finally, it is an object of our invention to provide a device of the character indicated that will be economical to manufacture, easily made in various sizes to accommodate various sizes of brushes, of few parts, simple in construction, and highly efficient in its practical application.

In the drawing:—

Figure 1 is a front elevation of the device in position on a brush.

Figure 2 is a side elevation of the same. Figure 3 is a section on line 3—3 of Figure 1.

Figure 4 is a sectional view through another embodiment of our invention.

Referring more particularly to the draw-

ing, 1 and 2 indicate the two side portions 55 hinged together at 3 and provided with wedge shaped end portions 4. The edges of the end portions 4 of part 1 are folded upon themselves to form grooves 5 adapted to receive the edges of portions 4 of part 2, thereby forming a tight joint when the two parts are folded together on a brush.

In its practical application, several sizes of these devices are made to conform to the several standard sizes of brushes, the combined upper edges of parts 1 and 2 being so formed and proportioned as to fit snugly around the brush and butting up against the under surface of body portion 6, the latter carrying a handle 7.

The interlocking side edges, hinged bottom edges and snugly fitting top edges effectually seals the bristle portion of the brush off from contact with the air and consequently preserves the brush in a soft and flexible condition. Furthermore, since the shape of the device conforms closely to the shape of the brush, it causes the brush to retain its normal shape when not in use.

The combined features of preventing the drying of the paint on the brush and maintaining it in a normal shape greatly increases the effective life of the brush and obviates the necessity of spending considerable time in cleaning the brush every time it is laid aside for a little while.

In order to positively secure the two parts 1 and 2 in a closed position on a brush in close contact with the body portion 6 thereof, any suitable clamp may be used such as spring elements 8 hingedly mounted as at 9 on one element as 1 and capable of being swung into the positions clearly shown in Figure 3 to grasp the element 2.

If it is desired to secure the device to the brush a suitable fastener may be used. In the present case we show a member 10 mounted on the device as shown and carrying an outwardly extending lip 11 provided with an eye 12. On member 10 and adjacent to eye 12 is formed a button or boss 13. At 14 we show a resilient strip provided with a hooked end 15 adapted to engage the upper surface of body portion 6, the other end being provided with orifices 16 adapted to engage boss 13, the said strip passing through eye 12. By means of this construction the device may be held firmly in posi-

tion, the adjustable strip 14 permitting its application to brushes having body portions 6 of various thickness.

As clearly shown in Figure 4, the parts 1 and 2 may be made to clasp the sides of the body portion 6 if so desired.

It is to be understood, of course, that while we have herein shown and described the preferred embodiments of our invention, changes in form, construction and method of operation may be made within the scope of the appended claims.

We claim:—

1. A paint brush protector comprising a pair of jaws hinged together at one end and having triangular shaped interlocking sides, and an element mounted thereon and extending beyond one end thereof and adapted to engage the body portion of a brush placed therein.

2. A paint brush protector comprising a pair of jaws hinged together at one end and having triangular shaped interlocking sides, and a longitudinally adjustable spring

element mounted thereon and adapted to engage the body portion of a brush placed therein.

3. A paint brush protector comprising a pair of jaws hinged together at one end and having triangular shaped interlocking sides, and spring elements mounted upon one of said jaws and adapted to be swung into engagement with the other of said jaws whereby to hold said jaws in closed relation to each other.

4. A paint brush protector comprising a pair of jaws hinged together at one end and having triangular shaped interlocking sides, a longitudinally adjustable spring element mounted thereon and adapted to engage the body portion of a brush placed therein, and spring elements mounted upon one of said jaws and adapted to be swung into engagement with the other jaw whereby to hold said jaws in closed relation to each other.

LEONARD H. BROWN.
RUDOLPH MALMGREN.
